UNITED STATES PATENT OFFICE.

MINNIE S. KARR, OF NEWARK, NEW JERSEY.

FASTENING-PIN.

No. 893,171.

Specification of Letters Patent.

Patented July 14, 1908.

Application filed June 26, 1907. Serial No. 380,850.

To all whom it may concern:

Be it known that I, MINNIE S. KARR, of the city of Newark, county of Essex, and State of New Jersey, have invented a new 5 and useful Improvement in Fastening-Pins, of which the following is a full, clear, and exact description.

My invention relates to improvements in pins which are especially adapted for hat pins, 10 but which can be used for other purposes; as for draping cloth or other fabric.

It is generally recognized that an exposed 15 pin point on a woman's clothing or hat is unsightly and dangerous, and well dressed people object to anything of the sort. Moreover, the pin which has an exposed point is likely to work loose and be lost. Thus the owner may lose a valuable pin, or if the pin 20 is not of any particular value, the discomfort resulting from a loose hat is annoying.

The object of my invention is to overcome 25 these difficulties, and to produce a simple pin which carries in its head or on its head, a sheath for the point of an opposed pin, so that pins can be used in pairs, and the point of one made to enter the sheath in the head of the other, whereby the two pins are locked together, and the hat or other article or device to which the pins are secured, is 30 firmly fastened. It will be seen that this arrangement also guards the points and prevents them from being seen. In carrying out this idea, it is obvious that the head can be made up in any preferred design, that it 35 can be as ornamental as required, and that the sheath to receive the point of an opposing pin may be a piece of cork, compressed felt, or anything which will receive and engage the point so as to prevent it from readily be- 40 coming loose.

With these ends in view my invention consists of a combination pin and sheath, which will be hereinafter clearly described and the novel features claimed.

Reference is to be had to the accompanying 45 drawing forming a part of this specification, in which similar reference characters indicate corresponding parts in all the views.

Figure 1 is a sectional view showing the application of a pair of pins embodying my 50 invention, to a hat. Fig. 2 is a view partly in section, showing two pins connected, but with one shorter than the other, and having its point free. Fig. 3 is a face view of a modification of the invention, showing different

forms of pins. Fig. 4 is a sectional side elevation of the structure shown in Fig. 3, and Fig. 5 is a detail sectional view of another form of the pin head.

The pin 10 can be of any usual structure 60 and of any desired length. It has the usual free point, and a head 11 at the end, which head can be made up in any desired shape, but which carries a sheath or cushion 12, to receive the point of an opposed pin. In 65 the drawing, Fig. 1, I have shown the head having a hollow structure in which can be placed felt, sponge, cork, or other compressed substance soft enough to receive a pin point, and having sufficient friction to grip it somewhat. It will be obvious that these pins can be used precisely as usual, except that the point of one enters the sheath of the other. The pins are pushed in through the hat at 70 opposite sides, they engage the hair as usual, and a little practice will enable the user to make the points register perfectly with the sheath heads. When fastened as shown, they secure the hat firmly.

In Fig. 2 I have shown one of the pins 80 shorter than the other, to illustrate the fact that if used as a hat pin, the head of one can be made as a sheath for the point of the other, and the short pin can be allowed to float around in the hair.

In Figs. 3 and 4 I have shown a pin which, while it may be used for a hat pin, is especially designed for fastening garments, for draping cloth, or other fabric. Short pins of this character are also especially useful 90 and ornamental in millinery. Here the pin extends from the back of a generally flat head 13, which can be made as ornamental as desired, and which has a sheath or cushion 14 on the under side, this sheath being merely a 95 piece of cork, sponge or felt, which can be compressed for the purpose. It is better, however, to make a pin of this sort with a casing 15 on the back side, as in Fig. 5, to receive the compressed sheath 16, as in such a structure as this the sheath is more durable and less likely to be disintegrated by numerous pricks from a pin point.

I am aware that it is not new to provide a 105 sheath for a pin point, but I have no knowledge of the fact that a pin has been provided with a head that serves the purpose also of a sheath, and it will be seen that the pins embodying my invention are used to the best advantage in pairs.

Having thus fully described my invention, I claim as new and desire to secure by Letters Patent:—

1. As an improved article of manufacture, a pin having its head provided with a cushioned sheath.
2. A pin having its head formed with a

casing containing a point receiving sheath arranged to receive the point of an independent opposed pin.

MINNIE S. KARR.
